UNITED STATES PATENT OFFICE

EDWARD MADDEN, OF AMSTERDAM, NEW YORK.

VAPORIZER.

1,020,430.

Specification of Letters Patent. Patented Mar. 19, 1912.

Application filed January 6, 1911. Serial No. 601,229.

To all whom it may concern:

Be it known that I, EDWARD MADDEN, citizen of the United States, residing at No. 15 Kimball street, Amsterdam, in the county of 5 Montgomery and State of New York, have invented certain new and useful Improvements in Vaporizers; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

This invention relates to improvements in vaporizers.

The object of the invention is to provide means for vaporizing various chemicals in 20 a series of vaporizers and introducing the gases to a mixing chamber common to all the vaporizers and into which said vapors pass, and from which they are drawn to a patient.

25 A further object of the invention is to provide means, whereby one or a combination of gases may be drawn from the mixing chamber to treat a patient.

The invention also comprehends improvements in the details of construction and arrangement of parts which will be hereinafter described and particularly pointed out in the claims.

Figure 1 is a plan view. Fig. 2 is a vertical central section on the line A—A, Fig. 1. Fig. 3 is a horizontal section on the line B—B, Fig. 2. Fig. 4 is a side elevation of the apparatus.

The numeral 1 indicates a tank to hold a 40 volume of water, indicated at 2, to be used as medium for vaporizing the chemicals.

3 indicates a top provided with a depending annular flange 4, which fits within the tank 1, and in addition to this flange, the 45 top is formed with several separate depending annular flanges 5, for supporting an equal number of chambers, 6, 6^a, 6^b, 6^c, 6^d, 6^e. The central chamber 6^c, is what I will term a mixing chamber, while the remaining 50 chambers are vaporizing chambers, into which the various chemicals and gases are introduced.

Fitting in an opening in the top 3, over the vaporizing chambers are valves 7, 7^a, 7^b, 55 7^c, 7^d and 7^e from the lower end of which depend pipes 8, 8^a, 8^b, 8^c, 8^d and 8^e, extending

down within a short distance of the bottom of the chamber. Each valve comprises a casing and a valve proper, the latter fitting snugly on a seat 8^e. The valve proper is surrounded by a chamber 9, formed in the casing, with which pipes 10 communicate, each pipe leading to the adjacent valve casing over the vaporizing chambers.

Leading into one of the valve casings are 65 two pipes 12 and 13, the pipe 12, having a valve 15, while pipe 13, is provided with a valve 15'. To the pipe 12, is connected a tube leading to a source of supply of oxygen (not shown) and to the pipe 13 is connected a tube leading to a source of compressed air (not shown).

Located in the top 3 and over the vaporizing chambers, are valves 17, 17^a, 17^b, 17^c, 17^d and 17^e connected by short pipes 18, with 75 coupling members 19, 19^a, 19^b, 19^c, 19^d and 19^e to which pipes 20 are attached. The pipes 20 extend down within the mixing chamber 6^c, to within a short distance of the bottom thereof, and each of said pipes is curved inwardly at its bottom to cause a thorough intermixing of the gases when the apparatus is in use.

Extending from the top 3, and communicating with the mixing chamber 6^c, is an 85 outlet pipe 21. Extending from the pipe 21 are two pipes 23 and 23^a, provided with valves 24 and 24^a. On the ends of these pipes are tubes 27 and 27^a, to the ends of which may be secured a spraying or other 90 device for conveniently applying the vapors for medical use and to the pipe 27, may be attached a bulb 22, as shown in Fig. 1.

The valves 7, 7^a, 7^b, 7^d and 7^e have pointers 30, 30^a, 30^b, 30^d, and 30^e, which operate over dials 31, 31^a, 31^b, 31^d, and 31^e. The pointers operating over the dials indicate the flow of gas passing from the chambers 6, 6^a, 6^b, 6^d, and 6^e.

Handles 32, are secured to the top 3, for 100 convenience in handling the apparatus.

The tank 1, is provided with legs 33 to support the apparatus and to form a convenient space between a false bottom 34, and the bottom of the tank for a burner 35. 105 The burner 35 is connected to a pipe 36 having a valve 37 leading to a source of gas supply for the purpose of heating the water in the tank 1. In order that the temperature of the water in the tank may be observed by 110 the operator, a thermometer 38, is located in the side of the tank, as indicated in Fig. 4,

and in order that the pressure at the outlet pipe 21 may be observed a pressure gage 39 is attached to the pipe 21, a portion of which is shown in Figs. 2 and 4.

5 In Fig. 2, the pipe 8, is provided with a nebulizer 40 which may or may not be used, depending altogether upon the nature of the oil or chemical placed in the chamber 6.

In operation, such chemicals as may be 10 desired are introduced in the vaporizing chambers appropriate to the treatment of a stated case, and then the top is placed on the tank 1, with the lower ends of the vaporizers immersed in the water 2 and the gas 15 is ignited at the burner 35, to heat the water, as is the custom in an apparatus of this character. When nebulizing or vaporizing of the chemicals or substances in the various chambers has taken place, the operator may 20 by manipulating the various valves in the pipes leading from the vaporizing chambers to the mixing chamber, allow a flow of selected vapor or gas to pass into the mixing chamber. Obviously, by manipulating 25 the valves 17, 17^a, 17^b, 17^c, 17^d and 17^e one or more, of the various gases or vapors in the chambers may be introduced to the mixing chamber according to the treatment desired. If the treatment warrants the use of a cer- 30 tain chemical gas or vapor from any particular chamber, the corresponding valves are turned to shut off the supply, so that only the gas from the chamber selected will pass to the mixing chamber and thence from the 35 outlet pipe 21 to the distributing pipes 23 and 23^a. On the other hand, if a mixture of such gases or vapors is desired, the respective valves of the chambers containing the particular gases will be opened to be intro- 40 duced to the mixing chamber, and by means of the ends of the depending pipes 20 being curved at their lower ends toward each other a thorough mixing of the gases takes place before passing through the exit pipe 21.

45 To distribute the gases under pressure through the pipes 23, 23^a, the valve 15' in pipe 13 is opened and the valve 15 in pipe 12 is closed, and the air under pressure will pass through the respective connecting pipes 50 10 and into the chambers forming part of the valves 7, 7^a, 7^b, 7^c, 7^d, 7^e. By opening the valves 7, 7^a, 7^b, 7^c, 7^d, and 7^e the air will pass down through the pipes 8 into the chambers and thereby force the gas or vapor therefrom 55 and into the mixing chamber. The pipes 12 and 13, as previously stated, are connected respectively to a source of supply of oxygen and a source of supply of compressed air, said pipes being controlled by the valves 60 15 and 15'. Assuming that the chemical is to be vaporized in cylinder 6^a, the valve stems of all the valves 7, 7^a, 7^b, 7^c, and 7^d will be screwed down to close communication with their respective chambers. Valves 7^e 65 and 17^e, will be opened to afford communica-

tion with the chamber 6^e. The supply of oxygen having now been completely cut off by means of the valve 15 in the pipe 12, and the valve 15' in the air pipe 13 being opened, a supply of compressed air enters 70 the valve 7^e over the chamber 6^e, and into the annular chamber surrounding the valve stem. This space communicates by means of the pipes 10 with similar chambers in the corresponding valve casings of the valves 75 7, 7^a, 7^b, 7^c, 7^d, and 7^e. The compressed air passes through the pipe 8^e in chamber 6^e and forces the vapor generated therein upward through valve 17^e which has previously been opened, through the pipe 18 and vertical 80 pipe 20 into the mixing chamber 6^e. From this chamber the vapor under pressure passes through the outlet pipe 21 to the distributing pipes 23. One of these pipes is to be used when a patient is able to endure the 85 full pressure from the compressed air supply from pipe 13. The other distributing pipe 23 is to be used in connection with a bulb 22. This bulb receives a charge by suction and the charge is discharged by compression and 90 is intended to be used only when gentle application of the vapor is to be made, which result is effected by the hand of the operator rather than by the greater pressure from the tank from which the air is supplied. 95 When administering oxygen, the cut off valve 15' in pipe 13 is closed and communication may be had with only one or several of the vaporizing chambers by manipulating the valves. If oxygen alone is to be ad- 100 ministered, all of the outside valves 7, 7^a, 7^b, 7^c, and 7^d, will be closed. Valves 17^e will re- main open to afford communication with the chamber 6^e. The oxygen under pressure is forced through pipe 12 into the valve case 105 7^e, down through the vertical pipe 8^e and into the warming chamber 6^e, then out through the valves 17^e and the pipes 18 and 20 and into the mixing chamber 6^e, thence through the outlet pipe 21 into either of the distributing 110 pipes 23, 23^a to be used under direct pressure or through the medium of the hand bulb as above described. When a mixture of oxygen and air is desired, the same is accomplished by a proper manipulation of the 115 valves 15 and 15' in the pipes 12 and 13.

By arranging the parts as described, a convenient and compact apparatus is provided which may be used for medicinal purposes and by the manipulation of the valves, various mixture of gases, or a particular gas, may be employed in the treatment of a case as the circumstances may require.

What I claim is:

1. In an apparatus of the class described, the combination of a tank adapted to hold a volume of water, means for heating the water in the tank, a top on the tank, said top having a plurality of depending flanges, a plurality of vaporizing chambers supported 120

by the depending flanges and extending in the tank, a casing provided with a valve and having a depending pipe fitting in each of the chambers, said valve casing having a 5 chamber formed therein above the seat with which the valve co-operates, all of said latter casings being connected by pipes, a pipe communicating with one of the aforesaid valve chambers for supplying oxygen there- 10 to, a pipe connected to the same valve chamber for supplying air pressure thereto, a second valve communicating with each of the said vaporizing chambers, each of said valves having a pipe leading therefrom and 15 communicating with the central one of said chambers and terminating near the bottom of the latter, an exit pipe leading from the central chamber, and distributing pipes leading from the exit pipe.

2. In an apparatus of the class described, the combination of a tank adapted to hold a volume of water, means for heating the water, a top for said tank, said top having a series of annular flanges, a series of vaporizing chambers supported by said flanges, a pipe leading from each of said chambers and terminating near the bottom thereof, a valve in each of said pipes, said valves having chambers therein, a system of pipes connecting all of said valves, means for supplying said valves with a supply of air, means for supplying said pipes with a supply of oxygen, a mixing chamber supported on one of the annular flanges on the top, a 25 series of pipes corresponding to the number of vaporizing chambers extending 30

through the top and into the mixing chamber, the lower end of said pipes being turned inwardly toward each other, a valve for each of the latter pipes, an exit pipe leading from the mixing chamber, and a series of distributing pipes connected with the bulb. 40

3. In an apparatus of the class described, the combination with a tank adapted to contain water, means for heating the water, a top for the tank, a series of depending flanges on the top a series of chambers supported by the flanges and extending in the tank, each of said chambers having a pipe 50 terminating near the bottom, a valve in each pipe, a second valve for each of said chambers, a mixing chamber centrally located with reference to the aforesaid chambers and supported by one of the depending 55 flanges, pipes depending in the mixing chamber and connected with the second mentioned valves, the lower ends of said pipes being turned inwardly toward each other and means for supplying the first 60 mentioned valves with a supply of air or oxygen, an outlet pipe extending from the mixing chamber, and a bulb on the outlet pipe.

In testimony whereof I have signed my 65 name to this specification in the presence of two subscribing witnesses.

EDWARD MADDEN.
